UNITED STATES PATENT OFFICE.

JOHN T. HINTON, OF MOULTRIE, GEORGIA.

COMPOUND ENGINE VALVE.

1,409,110.

Specification of Letters Patent.

Patented Mar. 7, 1922.

Application filed May 25, 1920. Serial No. 384,136.

To all whom it may concern:

Be it known that I, JOHN T. HINTON, a citizen of the United States, residing at Moultrie, in the county of Colquitt and State 5 of Georgia, have invented certain new and useful Improvements in a Compound Engine Valve, of which the following is a specification.

This invention relates to improvements 10 in engine valves and the mechanism whereby they are operated, and has for one of its objects to simplify and improve the construction and increase the efficiency and utility of devices of this character.

Another object of the invention is to provide a device of this character which is substantially silent in action, can be utilized 15 to reverse the engine, has the minimum of friction owing to the reduced number of parts, freer and faster action of the gases, and reduction in the cost of manufacture.

With these and other objects in view, the invention consists in certain novel features 20 of construction as hereinafter shown and described and then specifically pointed out in the claims, and in the drawings illustrative of the preferred embodiment of the invention,

Figure 1 is a vertical sectional elevation 25 showing the valve in "exhaust" position.

Figure 2 is a similar view showing the slide valve closing the exhaust and opening the inlet port, the poppet valve wide open, and the crank slightly past the upper dead 30 center.

Figure 3 is a similar view showing the slide valve at the lower end of the stroke, the inlet port open and the poppet valve moving toward closing position.

Figure 4 is a similar view with the valve 35 at the upper end of its stroke with the slide valve moving toward exhaust position and the poppet valve closed.

Figure 5 is an enlarged detail of the joint 40 between the poppet valve stem and the connecting rod of the eccentric.

Figure 6 is a transverse section on the line 45 6-6 of Fig. 1.

Figure 7 is a detail illustrating the arrangement of parts to produce a reversing 50 mechanism.

The improved device is designed for use 55 in connection with internal combustion engines, and for the purpose of illustration is shown applied to an engine of this class including the cylinder 10, piston 11, crank

shaft 12 having the crank 13 coupled to the piston by the usual connecting rod 14.

Formed in the upper end of the cylinder is a cylindrical valve seat 15 in which a 60 plunger slide valve 16 is arranged to operate.

An intake port 17, and an exhaust port 18 communicate with the seat 15 one above the other.

The valve 16 is formed with ports 21 providing communication through its sides and opening downwardly, as shown at 22. The ports 21 are in alignment transversely of the valve and are alternately disposed in registering relation to the exhaust and intake 65 ports.

The valve 16 is centrally bored to receive the stem 23 of a poppet valve 24, the latter adapted to engage an annular seat 25 at the lower end of the cylindrical seat 15. The 70 stem 23 is tubular at the outer end, and connected within the tubular portion by a combined ball and socket and yieldable joint 75 is a connecting rod so that the poppet valve may be moved to a limited extent independently of the movement of the main valve 16. At the inner end of the tubular portion of the stem 23 a semi globular socket 27 is formed to receive the ball shaped terminal 80 28 of a rod 29.

At its outer end the bore of the stem 23 is internally threaded to receive a stop washer 85 30 through which the rod 29 passes, the opening in the washer being sufficiently large to permit the rod to have considerable lateral play.

Slidable in the stem 23 is a sleeve 31 having a socketed lower end 32 to engage the ball shaped terminal 28 of the stem 29. A spring 33 is disposed within the sleeve and 90 bears upon the socket portion 32 and beneath the stop washer 30.

By this means a longitudinally yieldable joint is produced between the stem and rod.

Mounted on a shaft 35 and supported in 100 any suitable manner relative to the engine frame or cylinder 10, is an eccentric 36 including a strap 37, the rod 29 being extended and connected to the eccentric strap as shown at 38. By this arrangement when 105 the shaft 35 is rotated motion will be imparted to the stem 23 and the valve 24 carried thereby.

Extending from the cylinder body 10 is a bracket 39, and pivoted at 40 on the bracket 110 is a two-part bell crank lever 41, the latter being coupled by one pair of its arms to the

opposite sides of the valve 16 by links 43. By this means the valve will be actuated without producing side strain. The other arms of the bell crank levers are coupled by 5 a link 43 to the eccentric strap device 37. The rod 29 and link 43 are coupled to the eccentric strap about $93\frac{1}{2}$ ° apart, as indicated.

By this arrangement the main cylindrical slide valve 16 and the poppet valve 24 are 10 operated simultaneously by a single eccentric, while at the same time the poppet valve is permitted to have a slight independent or yieldable movement by reason of the spring controlled coupling between the eccentric 36 and the stem 23. The ball and socket feature between the rod 29 and the stem 23, permits the action of the eccentric without producing strain.

By this arrangement the movements are 20 accomplished practically without noise, as there are no loose cam devices to produce pounding noises.

The motion may be reversed by employing 25 two eccentrics 44 and 45 and a segmented link 46 of the ordinary construction, as illustrated in Figure 7.

The eccentrics 44 and 45 are connected by arms 47 and 48 to the curved slotted link 46. Slidable in the slot of the link is 30 a block 49 the latter pivoted at 40 to the vertical arm of the bell crank lever 41.

The link 46 is suspended by a hanger 52, to which an operating lever 53 is coupled by a connecting rod 54.

35 The lever 53 operates over a toothed segment 55 with which a pawl device 56 carried by the lever 53 engages.

By this arrangement the curved link 46 may be adjusted on the block 49 to any required extent within the range of the slot 40 of the link and locked in adjusted position.

The pin 50 operates the valve 16 through the action of the bell crank lever 41.

The link 46 as shown brings the pin 50 45 in line with the eccentric rod 47 and the motion imparted to the valve will be the same as if there were only one eccentric 44, the other eccentric 45 running idle.

By elevating the link 46 to its upper position, to bring the rod 48 in line with pin 50, the eccentric 44 will run idle and the eccentric will control the motion of the valve 16 and the direction of rotation of the shaft 12 will be reversed, in the ordinary manner 55 of devices of this character.

The shaft 35 is driven from the main shaft 12 in any suitable manner, for instance by chain wheels 57 and 58 and chain 59 as indicated in Figure 1 of the proper proportions. Generally the wheel 57 will be double the size of the wheel 58 to produce the required motion.

In Figure 1 of the drawings, the parts are shown arranged with the exhaust of the 60 main valve 16 open and the crank 13 posi-

tioned ahead of the lower dead center about 20° and with the poppet valve just beginning to open. In this position, (which is the end of the firing stroke), the main valve 16 is wide open and the hot gases will pass 70 out around the poppet valve 24 as the piston travels in the up stroke to 7 degrees past the upper dead center. This will heat the poppet valve 24.

Figure 2 shows the relative location of 75 the parts when the crank 13 is positioned about 7° past the upper dead center and the main valve 16 closing the upper exhaust port and about to open the lower inlet port with the poppet valve 24 wide open. At 80 this point the hot gases will have passed out and around the poppet valve 24 and the cold gases will come in around the poppet valve 24 with the effect of cooling the valve and at the same time heating the incoming gases.

Figure 3 shows the relative location of the parts when the crank 13 is positioned about 20° past the lower dead center, the main valve 16 at the lower end of its stroke 90 with the lower inlet port open, the exhaust port closed and the poppet valve 24 just closing. At this point the poppet valve 24 closes and on the up stroke of the piston the gas is compressed and the main valve 95 16 is being drawn back into exhaust position. The poppet valve being closed cuts off all connection between combustion chamber and main valve 16.

Figure 4 shows the relative location of 100 the parts when the crank 13 is positioned at the lower dead center, the main valve 16 returning to exhaust position, and the poppet valve 24 closed. The engine fires when the parts are shown as in Figure 4, 105 with the poppet valve 24 closed, the pressure of the compression stroke and burning gases on the firing stroke are not admitted to the slide or main valve 16. This makes it possible to use continuous eccen- 110 trics instead of irregular cams in the operation of the valves.

The spring in the connection between the poppet valve and the eccentric allows the poppet valve to be held in position from 115 20° past dead center to 20° ahead of dead center on the compression and firing stroke.

This operation is necessary in order to enable the eccentric to be used in connection with the poppet valve 24, but is not 120 objectionable as the working stroke of the ball socket is only about $\frac{7}{64}$ on a 2" valve.

The preferred embodiment of the invention is disclosed in the drawings and set forth in the specifications, but it will be 125 understood that any modifications within the scope of the claims may be made in the construction without departing from the principle of the invention or sacrificing any 130 of its advantages.

What I claim is:

1. An engine including a body having cylinder and a cylindrical valve seat communicating with the cylinder and with an inlet and an exhaust port in spaced relation, a piston operative in said cylinder, a shaft connected to be operated by said piston, a centrally bored major valve movable in said seat and having ports providing communication with the cylinder and alternately communicating with said inlet and exhaust ports, a minor valve adapted to be seated between the cylinder and the valve seat and including a stem operative through the bore of the major valve, an eccentric device including an eccentric strap connected for operation from the shaft, a bell crank element mounted on the engine body, means for operatively coupling said eccentric strap to said minor valve, connecting means between said major valve and one arm of said bell crank lever, and connecting

means between said major valve and the other arm of said bell crank lever.

2. An engine including a cylinder having a valve seat communicating therewith and provided with an inlet and an exhaust port in spaced relation, a piston operative in said cylinder, a shaft connected to be driven by said piston, a major valve movable in said valve seat and having ports providing communication with the cylinder and alternately communicating with said steam and exhaust ports, a minor valve adapted to be seated between the cylinder and valve seat, valve operating means connected for movement by said shaft, coupling means between said major valve and the operating means, and longitudinally yieldable coupling means between the minor valve and the operating means.

In testimony whereof, I affix my signature hereto.

JOHN T. HINTON.
